No. 36,389.

Patented June 30, 1903.

UNITED STATES PATENT OFFICE.

FREDERICK E. PRETAT, OF WATERBURY, CONNECTICUT, ASSIGNOR TO INTERNATIONAL SILVER CO., OF MERIDEN, CONNECTICUT, A CORPO-RATION OF NEW JERSEY.

DESIGN FOR A HANDLE FOR SPOONS, FORKS, OR SIMILAR ARTICLES.

SPECIFICATION forming part of Design No. 36,389, dated June 30, 1903.

Application filed June 2, 1903. Serial No. 159,832. Term of patent 7 years.

To all whom it may concern:

Be it known that I, FREDERICK E. PRETAT, of Waterbury, in the county of New Haven and State of Connecticut, have invented and 5 produced a new, original, and ornamental Design for a Handle for a Spoon, Fork, or Similar Article; and I do hereby declare the accompanying drawing to be a full, clear, and exact illustration of the same, and which said 10 drawing constitutes part of this specification, and represents a face view of a handle for a spoon, fork, or similar article.

I claim—

The ornamental design for a handle for a spoon, fork or similar article as shown. 15

In testimony whereof I have signed this specification in the presence of two subscribing witnesses.

FREDERICK E. PRETAT.
